Primary Examiner — Sandra Snapp*(74) Attorney, Agent, or Firm* — Jeffrey Schox(57) CLAIM

We claim the ornamental design for a pendant for sexual stimulation, as shown and described.

DESCRIPTION

FIG. 1 is an isometric view, from the back left, of the pendant for sexual stimulation; and,

FIG. 2 is an elevation view of the front of the pendant for sexual stimulation;

FIG. 3 is an elevation view of the right side of the pendant for sexual stimulation;

FIG. 4 is an elevation view of the back of the pendant for sexual stimulation;

FIG. 5 is an elevation view of the left side of the pendant for sexual stimulation;

FIG. 6 is a plan view of the top of the pendant for sexual stimulation; and,

FIG. 7 is a plan view of the bottom of the pendant for sexual stimulation.
